Design No. 12,107, dated January 11, 1881.

UNITED STATES PATENT OFFICE.

CHARLES H. BUCK, JR., OF ST. LOUIS, MISSOURI, ASSIGNOR TO CHARLES H. BUCK, SR., OF SAME PLACE.

DESIGN FOR A HEATING-STOVE.

SPECIFICATION forming part of Design No. 12,107, dated January 11, 1881.

Application filed November 20, 1880. Term of patent 7 years.

To all whom it may concern:

Be it known that I, CHARLES H. BUCK, Jr., a citizen of the United States, residing at the city of St. Louis, Missouri, have invented and produced a new and original Design for Heating-Stoves, of which the following is a specification, reference being had to the accompanying engraving, forming part thereof, in which the stove is shown in perspective.

10 The leading features of my design consist in the peculiar form of the base of the stove, substantially as hereinafter more fully described, in the waved or scalloped outline of the side foot-rail and of the side door-frame, and in the ornamentation upon the base, upon 15 the body of the stove, and upon the end plates.

Referring to the engraving, A represents a stove having the features in question.

The base B consists of the square legs C C, 20 having the sides or parts c c arranged at an angle to each other, and the connecting-arches D D, which extend between the legs.

E E represent the end plates of the stove. The edges e are scalloped, as shown, forming 25 the points e' e'. The side foot-rail, F, is also pointed at f f and the side door-frame, G, at g g, producing, generally considered, the same effect as the scalloped outline of the end plates. The front end plate, E, may also have 30 a scalloped escutcheon, H.

All the various parts of the stove are ornamented, the legs having the designs c' c', the arches the designs d d, the end plates the 35 tracery and the figure of a buck, e' e', the escutcheon the stars and crescent h, and the body I of the stove the designs i i' i'', all of which ornamentation being formed as intaglios.

I claim—

1. The design for a heating-stove herein shown and described, the same consisting of 40 the square legs C, having the parts c c arranged at an angle to each other.

2. The design for a heating-stove herein shown and described, the same consisting of the base B, having the legs C C connected by 45 the arches D D.

3. The design for a heating-stove herein described and shown, the same consisting of the scalloped side foot-rail, F, having the points 50 f f.

4. The design for a heating-stove herein shown and described, the same consisting of the scalloped side door-frame, G, having the points g g.

5. The design for a heating-stove herein 55 shown and described, the same consisting of the scalloped escutcheon H.

6. The design for a heating-stove herein shown and described, the same consisting, in combination, of the scalloped end plate, E, 60 and the scalloped escutcheon H.

7. The design for a heating-stove herein shown and described, the same consisting of the top plate, J, having the designs j j.

8. The design for a heating-stove herein 65 shown and described, the same consisting of the body I, having the designs i i' i''.

C. H. BUCK, JR.
